Primary Examiner — Katie Jane Stofko*(74) Attorney, Agent, or Firm* — McAndrews, Held & Malloy, Ltd.(57) **CLAIM**

The ornamental design for an ice cream, as shown and described.

DESCRIPTION

FIG. 1 is a front perspective view of an ice cream showing my new design according to a first embodiment; and, FIG. 2 is a front perspective view of an ice cream showing my new design according to a second embodiment. The dashed broken lines in the figures illustrate an environmental ice cream container that forms no part of the claimed design.

1 Claim, 2 Drawing Sheets**FIG. 1**

FIG. 2
